UNITED STATES PATENT OFFICE.

HUGO STOMMEL, OF ELBERON, NEW JERSEY, ASSIGNOR OF ONE-HALF TO AUGUST STAUDT, OF PERTH AMBOY, NEW JERSEY.

FRICITION-GEAR PRESS.

1,366,970.

Specification of Letters Patent.

Patented Feb. 1, 1921.

Application filed September 3, 1918. Serial No. 252,288.

To all whom it may concern:

Be it known that I, HUGO STOMMEL, a citizen of the United States, residing in Elberon, county of Monmouth, and State of New Jersey, have invented a certain new and useful Friction-Gear Press, of which the following is a specification.

Heretofore it has been common to make manually driven presses for floor and wall tiles, embossing or punching metal, paper, leather, etc., wherein the finished product has to be pushed out of the die by means of a manually actuated apparatus. The object of this invention is to provide a power driven press, of the character in question, which will relieve the operator of the manual labor of operating the press, his labor being confined to shutting the power on and off and inserting and removing material from the press.

This and other objects are accomplished by my invention, one embodiment of which is hereinafter more particularly set forth.

For a more detailed description of my invention, reference is to be had to the accompanying drawings, forming a part hereof, in which—

Figure 1 is a side elevation of a press provided with my improvement;

Fig. 2 is an end elevation of the same with a driving pulley removed;

Fig. 3 is a sectional view taken on the line 3—3 of Fig. 1, looking in the direction of the arrows; except that certain minor parts are omitted;

Fig. 4 is a side elevation partially in section taken substantially on the line 4—4 of Fig. 3, looking in the direction of the arrows; and

Figs. 5 and 6 show details of construction relating to a clutch by which the ejecting mechanism is thrown in and out of action.

My improved mechanism is applied to an ordinary press 1 which has a frame 2 and carries a screw threaded portion 3 at the top of the frame in which is mounted a screw 4 which is attached to a suitable cross head 5 that runs in any desired guide 6, all of which may be of the conventional or any other form desired. The press also is provided with a bed 7 which may carry any mold, die or other device used in the press, but as here shown a fixed die member 77 is illustrated, and passing through the bed are two parallel and screw threaded spindles 8

which may be attached to any particular means for ejecting the finished product of the mold in a manner which will be described below. As shown the spindles 8 support a movable die member 77.

The mold employed may be of any well known form but is preferably of the character shown and described in my co-pending application, Serial No. 288,166, filed April 7, 1919.

The screw 4 at its upper end is secured to a large wheel 9 which has a periphery composed of some friction material such as rubber, wood, leather or similar substance and this friction wheel 9 is adapted to engage either, but not both simultaneously, of two disks 10 and 11 fixedly held on a rotary shaft 12 which runs in suitable bearings 13 rising from brackets 14 which are fixed to the frame 2. One end of the shaft 12 has a small pulley 15 fixed thereon and beyond this is a second pulley 16 which carries a belt 17 by means of which the press is driven.

The upward movement of the screw 4 and wheel 9 is limited by means of a leaf spring 18 which is fixed to a bracket 19 which is secured to the rear of the part 3 of the frame 2 so that when the wheel 9 engages the spring 18, it is brought to a stop and held by frictional contact with this spring until lowered in a subsequent operation of the apparatus.

Power is delivered to the wheel 9 by means of the disks 10 and 11, as above stated, and these disks are so spaced that neither or one may be in contact with the wheel 9. When neither is in contact the wheel is idle. When one is in contact this wheel runs accordingly and the screw 4 is raised or lowered in the nut 3 according to the direction in which this wheel 9 is driven. If driven clockwise as one looks down upon it, it is lowered and if driven anti-clockwise it is raised. Under normal conditions it is assumed that the disk 10 drives the wheel 9 to compress whatever is in the mold or die 77 and the disk 11 works in the opposite direction to raise the cross head 5 through the screw 4. Whether either or neither of these disks shall operate to drive the wheel 9 depends on the position of the shaft 12 which has a sliding movement in the direction of its axis which is caused by means of a lever 20, fulcrumed at 21 in a

suitable support that comes from a bracket 14 and its upper end is provided with a bifurcated portion 22 which receives the ears 23 which extend laterally from a suitable 5 collar mounted so that the shaft 12 turns therein, but cannot move in the direction of its length with regard thereto. The lever 20 is a bent lever and at its lower end it is provided with a suitable pivotal connection 10 24 which in turn is pivoted to a link 25 that runs to a hand lever 26, fulcrumed at 27 and provided with a suitable dog 28 by means of which the lever 26 may be properly held in any of three positions. When 15 in its mid position, the disks 10 and 11 are off the wheel 9. When in its raised position, the disk 11 engages the wheel 9, and when in its lowered position the disk 10 engages this wheel 9. In any event, the 20 action of the disks on the wheel 9, if any, is determined by this lever 26.

It is obvious from the foregoing that the cross head 5 is shifted or not shifted according to the position of the hand lever 26 and 25 it is understood that the shifting of this cross head either up or down determines whether or not pressure is applied to or removed from whatever is in the mold on which the press acts. When the molding 30 operation has been completed, and it is desirable to eject the contents by actuating the rods 8 this is done in a mechanism which will now be described.

The rods 8, at their lower ends, are held 35 by nuts or other suitable means in a bracket 29 which spreads laterally from a suitable stem 30 which moves in the direction of its length a slight distance in a suitable guide 31 fixed to the base 32 of the machine. Near 40 its center, this stem 30 is recessed to receive a tooth 33 which is keyed or otherwise fixed to a shaft 34 mounted in suitable bearings 35 that also rise from the base 32 of the machine. Four of these bearings are employed although a greater or less number 45 may be used, if so desired.

One end of the shaft 34 is provided with a crank arm 36 which is fixed thereto and provided with a suitable crank pin 37 which 50 carries a block 38 which turns freely thereon and slides in a suitable guideway 39 in a link 40 which has two cap screws 41 mounted in suitable ears 42 by means of which the free movement of the block 38 in the slot 39 may be determined. The other end of 55 the link 40 has a pivotal connection with a suitable crank pin 43 fixed away from the center of a small spur gear 44 which has a shaft 45 mounted in a suitable bearing 46 60 that rises from a base 47 of a clutch mechanism. The spur gear 44 meshes with a pinion 48 with half its diameter and with half its number of teeth. This pinion is mounted on a suitable shaft 49 which runs in a bearing 50 which rises from the base 47. The

shaft 49 carries a disk 51 which is adjacent thereto and fixed to the shaft 49 and a housing 52 which carries a spring pressed bolt 53 which is kept in place by a cover plate 54 that is held by suitable screws, or other 70 securing means, and shifted by means of a depending tail 55 which is adapted to ride on a cam 56 which may be mounted in any suitable way as on a link 57 which is supported near each end by means of suitable 75 links 58 which rise from the base 47 and are pivoted thereto in any suitable manner. The link 57 is normally kept so that the cam 56 will engage the tail 55 because of a coil 80 spring 59 which is connected to the link 57 and also to an upright 60 which rises from the base 47 and is fixed thereto in any suitable manner. This link 57 may be pulled against the tension of the spring 59 so that the cam 56 will be clear of the tail 55 by a 85 mechanism which will be described below. When this cam 56 is clear of this tail 55, the spring of the bolt 53 will force it into a corresponding recess of a disk 61 mounted 90 on a suitable shaft 62 to which it is fixed and on the same shaft is also fixed a pulley wheel 63 which is in line with the pulley 15 and driven therefrom by means of a suitable belt 64. The shaft 62 is supported by a suitable bearing 65 that rises from the base 47. It 95 will be understood from the foregoing that when the machine is in operation the pulley 63 is driven continuously by the belt 64 and that the shaft 49 is driven only when the bolt 53 is in the groove in the disk 61. This 100 occurs when the cam 56 is withdrawn by a link 66 which is attached thereto and also to a crank arm 67 which is fixed to a shaft 68 that is journaled in suitable bearings 69 on the frame 2 of the machine and provided 105 with a small crank arm 70 that is pivotally connected to a link 71 that runs to a hand lever 72 pivotally mounted on a bracket 73 which extends from the frame 2 and adjacent to the lever 26 so that when the forward 110 end of the handle of the lever 72 is raised, the link 71 is lowered and the link 66 is thrown to the front of the machine and then the cam 56 is withdrawn against the tension of the spring 59 as above described. As 115 soon as the bolt 53 is in engagement with the disk 61 this disk drives the disk 51 and immediately thereafter the handle 72 is released and then the spring 59 acts to bring the cam 56 back into the path of the tail 55 120 so that when the disk 51 has made a complete revolution, the bolt 53 is withdrawn from the disk 61 and then the disk 51 ceases to move and remains at rest for the next operation of the machine. As the pinion 48 125 makes one complete revolution, the spur gear 44 which meshes with it makes one-half a revolution and this causes the link 40 to be shifted one-half of its throw and then come back to its point of rest which is at the mid 130

position and this imparts a corresponding oscillation to the crank 36 and the shaft 34 which is fixed thereto and this in turn imparts an elevating effect to the projection 33 and causes it to rise enough to lift the bracket 29 and raise the ejectors connected to the rods 8.

In view of the foregoing, the operation of my improved press will be readily understood. Assuming a suitable die or mold 77 is on the table 7 and the ejector or movable die member 77' is lowered and power is applied as indicated by the arrow at the right 21, the handle 26 is lowered and then the disk 10 is brought against the wheel 9 and the cross-head 5 lowered until sufficient pressure is put on the mold. Then the handle 26 is raised and the disk 10 is removed from the wheel 9 and the disk 11 is brought in contact with it and then the cross head 5 is raised until the wheel 9 comes in close contact with the leaf spring 18 which is its point of rest and then the lever 26 is thrown into its mid position so that both the disks 10 and 11 are off the wheel 9. The handle of the lever 72 is then raised and lowered, as above described, so that the ejecting rods 8 will operate to eject the product from the die or mold in the conventional manner and then the mold may be again filled and the cycle of operations above described may be indefinitely repeated.

While I have shown and described one embodiment of my invention, it is obvious that it is not restricted thereto, but is broad enough to cover all structures that come within the scope of the annexed claims.

Having thus fully described the invention, what I claim as new and desire to secure by Letters Patent, is:

1. A tile press embodying fixed and movable die members, an operating stem associated with the movable die member, a rock shaft, an arm on the rock shaft for reciprocating the operating stem when the rock shaft is actuated, a crank arm fixed to the shaft, a connecting rod coöperating with said crank to permit of loss motion in the connection between the crank and the connecting rod whereby the crank arm may partake of idle movement during the compressing of the tile without effecting move-

ment of the connecting rod, and a prime mover operatively associated with the connecting rod for actuating the rock shaft and positively operating the movable die member.

2. A tile press embodying fixed and movable die members, an operating stem associated with the movable die member, a rock shaft, an arm on the rock shaft for reciprocating the operating stem when the rock shaft is actuated, a crank arm fixed to the shaft, a connecting rod operatively connected with the crank arm, but adapted to permit loss motion in such connection, whereby the movable die member may be depressed to permit of the compression of the tile, without effecting movement of the connecting rod, a prime mover, and manually operable clutch mechanism between the prime mover and the connecting rod for rendering the connecting rod responsive or irresponsive to the operations of the prime mover.

3. A tile press embodying fixed and movable die members, an operating stem associated with the movable die member, a rock shaft, an arm on the rock shaft for reciprocating the operating stem when the rock shaft is actuated, a crank arm, fixed to the shaft, the connecting rod coöperating with said crank, a power driving shaft, a driven shaft, a counter-shaft geared to the driven shaft and provided with a crank for operating the connecting rod, and manually operable clutch members between the driving and driven shafts for rendering the connecting rod responsive or irresponsive to the operations of the driving shaft.

4. A power press embodying a friction wheel for operating the press, said wheel being mounted for simultaneous rotation and for movement longitudinally of the axis of its rotation, means for imparting rotation and longitudinal movement to the wheel and a plurality of the superimposed leaf springs adapted to be successively placed under compression through engagement with the wheel, for the purpose of bringing the wheel to rest at the terminus of its longitudinal travel.

In testimony whereof I have signed my name to this specification.

HUGO STOMMEL.
